No. 855,123.

PATENTED MAY 28 1907.

W. T. McNABB & F. ENDERS.

ICE TONGS.

APPLICATION FILED MAR. 27, 1907.

UNITED STATES PATENT OFFICE.

WILLIAM T. McNABB, OF BEN AVON, AND FRANK ENDERS, OF KITTANNING,
PENNSYLVANIA.

ICE-TONGS.

No. 855,123.

Specification of Letters Patent.

Patented May 28, 1907.

Application filed March 27, 1907. Serial No. 364,809.

To all whom it may concern.

Be it known that we, WILLIAM T. McNABB, residing at Ben Avon, in the county of Allegheny, and FRANK ENDERS, residing at Kittanning, in the county of Armstrong, State of Pennsylvania, citizens of the United States of America, have invented certain new and useful Improvements in Ice-Tongs, of which the following is a specification, reference being had therein to the accompanying drawing.

This invention relates to ice tongs, and the invention has for its object to provide novel means for closing a pair of tongs and automatically opening the same.

Another object of this invention is to improve the construction of ice tongs by increasing their strength, durability and efficiency.

A further object of this invention is to provide ice tongs that can be readily manipulated with one hand, thus leaving the other hand of an operator free to manipulate another similar device or perform other work.

With the above and other objects in view, which will more readily appear as the invention is better understood, the same consists in the novel construction, combination and arrangement of parts to be hereinafter more fully described and then specifically pointed out in the appended claims.

Referring to the drawing forming part of this specification, like numerals of reference designate corresponding parts throughout the several views, in which:

Figure 1 is a front elevation of our improved ice tongs partly in section, Fig. 2 is a side elevation of the same, Fig. 3 is a fragmentary elevation illustrating a slightly modified form of construction.

To put our invention into practice, we employ two metallic plates 1, each of which is formed with a central raised portion providing a sleeve or guide way when said plates are secured together by rivets 3.

Secured to the outer sides of the plates 1 by rivets 4 are the bifurcated ends 5 of a handle 6, said handle being substantially of a rectangular form adapted to accommodate the handle 7 of an actuating rod 8, said rod being movably mounted in the sleeve 2. Suitably secured to the handle 7 is a leaf

spring 9, said spring bearing against the under side of the handle 6 and normally holding the handle 7 in a lowered position.

The lower end of the actuating rod 9 is 55 provided with a cross head 10 and pivotally connected to said cross head, as at 11, are two hook-shaped members or tines 12, these members or tines being suitably shaped according to the use of our improved tongs. 60 The members or tines 12 are further connected by links 14 to the plates 1.

By referring to Fig. 1 of the drawings, it will be observed that the handle 6 is constructed of a strap, while the handle 7 is constructed from the upper end of the actuating rod 8. In Fig. 3 of the drawings, we have illustrated a slight modification wherein the rivets 3 and 4 are dispensed with and the plates 1 formed integral with the handle 6, 70 this construction reducing the expense of manufacturing the tongs.

In operation, it will be observed that it is only necessary to grip the handles 6 and 7 and compress the spring 9 to elevate the 75 actuating rod 8 and close the hook-shaped members or tines 12 upon the object to be elevated or lifted by the tongs.

Our improved tongs are constructed of strong and durable metal and we desire it to 80 be understood that such changes in the size, proportion and minor details of construction, as are permissible by the appended claims, may be resorted to without departing from the spirit and scope of the invention.

What we claim and desire to secure by Letters Patent, is:—

1. A pair of ice tongs consisting of connected plates, a sleeve formed by said plates, a handle connected to said plates, an actuating rod movably mounted in said sleeve and terminating in a handle within the first mentioned handle, a spring located between said handles for holding said actuating rod in a lowered position, a head carried by the lower end of said rod, hook-shaped members or tines pivotally connected to said head, and links connecting said members or tines with said plates, substantially as described.

2. A pair of tongs consisting of a sleeve, a handle located above said sleeve, an actuating rod slidably mounted in said sleeve and

terminating in a handle within the first mentioned handle, a spring mounted between said handle, hook-shaped members connecting with the lower ends of said rod, and links supporting said members upon each side of said rod.

3. A pair of tongs embodying plates providing a handle, a rod slidably mounted between said plates and terminating in a handle within the first mentioned handle, hook-shaped members connecting with the lower end of said rod, links connecting said members and said plates, and means interposed

between said handles for maintaining said rod in a lowered position.

In testimony whereof we affix our signatures in the presence of two witnesses.

WILLIAM T. McNABB.
FRANK ENDERS.

Witnesses to signature of W. T. McNabb:

MAX H. SROLOVITZ,
A. J. TRIGG.

As to Frank Enders:

HENRY JAMES,
ASA B. DE LONG.
